ELECTRIC SWITCH

Herschel C. Bolley, Clawson, Mich., assignor to
 H. A. Douglas Mfg. Co., Bronson, Mich., a corporation of Michigan

Continuation of application Serial No. 391,906,
 May 5, 1941. This application June 15, 1946,
 Serial No. 676,382

9 Claims. (Cl. 200—163)

1

This invention relates generally to electrical switches and more particularly has to do with an electric switch of the so called reciprocating type adapted to be mounted on an automotive vehicle.

This application is a continuation of my co-pending application Serial No. 391,906 filed May 5, 1941, now forfeited.

One particular object of the invention is to provide a switch having improved stationary contact means and improved movable bridge means which are cooperable in a unique manner whereby to control an electric circuit.

More specifically an object is to provide stationary contact means, of which part thereof is in the form of a contact plate which is connected to the switch casing in a manner whereby when the switch casing is secured to the vehicle, the plate is grounded thereto to establish one side of an electrical circuit.

Also, an object is to provide a contact plate of the character just referred to which serves to reinforce the switch casing.

Another object of the invention is to provide improved means for supporting or mounting the means which carries the bridge means.

A further object is to provide improved bearing means for the operating means of the switch.

A still further object is to provide an electric switch consisting of very few parts which are economical to manufacture and assemble on a production basis.

Other objects and advantages of the invention will become apparent after considering the description hereinafter set forth in conjunction with the drawing annexed hereto.

Referring to the drawing:

Figure 1 is a top view on an enlarged scale illustrating the switch embodying the invention;

Figure 2 is a vertical section taken substantially on line 2—2 of Figure 1, showing certain details of construction;

Figure 3 is a section taken substantially on line 3—3 of Figure 2, depicting certain details of construction with respect to the bridge means and carrier supporting same; and

Figure 4 is a partial view in elevation of Figure 2 showing the bridge means in position to close an electric circuit.

Referring to the drawing, the electric switch, among other things, includes, a switch casing designated 1, contact carrier means 2, bridge means 3 supported on a carrier 4, and an operat-

2

ing member 5 for moving the bridge means with respect to contact means associated with the contact carrier 2 for opening and closing an electric circuit.

The switch casing 1 is preferably made in the form of a box including, a bottom wall 6, side walls 7, and end walls 8 and 9. A generally rectangular contact plate 10 is supported by and closes off the upper open extremity of the casing 1. One extremity of the contact plate is preferably provided with a pair of spaced apart depending lateral portions 11 which engage the end wall 8 of the casing, and the opposite extremity of the contact plate is similarly provided with a pair of depending lateral portions 12 which engage the end wall 9 of the casing, as clearly shown in Figure 2. The contact carrier 2 of insulating material is superimposed upon the plate, and the plate and carrier are firmly anchored in place by means of a plurality of finger portions 13 and 14. The finger 13 is a continuation of the end wall 8 of the casing and projects upwardly between the lateral portions 11 of the contact plate and through a notch 15 provided therefor in the carrier 2, and is clinched over upon the carrier. The lateral portions 12 of the contact plate 10 which engage the end wall 9 of the switch casing are preferably provided with projections 16 which extend outwardly with reference to the planes formed by the side walls 7, as clearly illustrated in Figures 1 and 3. These projections 16 including the lateral portions 11 and 12 serve to hold the upturned end walls 8 and 9 of the casing in a predetermined position so that any strain placed thereupon due to the operation of the switch will not in any way distort or otherwise destroy the original shape of the switch casing. A notch 17 is preferably provided in each marginal edge of the plate 10 adjacent each of the lateral portions 12, and the carrier 2 with a complementary notch 18. The pair of finger portions 14, are continuations of the side walls 7 of the switch casing, and project upwardly through the notches 17 and 18, and are clinched over toward each other for securing the plate and carrier to the switch casing. Thus, it will be apparent that the contact plate 10 is both mechanically and electrically connected to the switch casing. In fact, since the plate provides a cover for the switch casing, it may be considered a part thereof. It should also be evident that the contact plate serves to reinforce the switch casing.

A terminal post 19 is carried by the contact carrier 2, and includes an upstanding portion 20 to which a conductor may be attached, and a base portion 21 which bears against the upper surface of the carrier 2. A headed contact rivet 22 is preferably employed to secure the post to the carrier. Its circular contact head 23 engages the lower surface of the carrier 2 and its stem portion projects upwardly through apertures provided therefor in the carrier 2 and the base portion 21 of the terminal post, and its upper end is overset upon the base 21, as indicated at 24 for permanently securing the post to the carrier. The contact plate 10, above referred to, is preferably provided with a relatively large circular aperture 25, and within this aperture 25 is disposed the contact head 23 of the rivet 22. The diameter of the aperture 25 is preferably somewhat greater than the diameter of the contact head 23 of the rivet so that the contact head can not engage the contact plate. In other words, the rivet is insulated from the plate. The thickness of the contact head 23 is preferably substantially the same thickness as the plate 10 so that the contact surface of the head will be disposed substantially flush with the lower surface of the plate. In order to positively prevent rotation of the terminal post 19 with respect to the carrier 2, the base portion 21 of the post is preferably provided with an integral lug portion 26 which projects downwardly into an aperture 27 provided therefor in the carrier, as clearly shown in Figures 1 and 2.

The manner in which the operating means or member 5 of the switch is mounted including the mounting means for the switch proper will now be considered. A circular aperture 28 is provided in the end wall 8 of the switch casing, and provides a bearing for one extremity of the operating member 5. A circular aperture 29 is provided in the end wall 9 of the switch casing directly opposite from the aperture 28. A tubular element 30 is preferably permanently secured to the end wall 9 of the casing. This element, among other things, is provided with an annular enlargement 31 which bears against the outer surface of the end wall 9, and projecting from this enlargement is a tubular portion 32 which fits in the aperture 29 and is flanged over and upon the inner surface of the end wall 9 to provide an abutment as indicated at 33. The hole 34 within the element 30 provides a bearing for the extremity 35 of the operating member, as clearly shown in Figure 2.

The tubular element not only serves as a bearing for the operating member, but also provides means for supporting the switch with respect to a support. This is preferably accomplished by providing the tubular element with threads 36 so that the element may be screwed into a tapped hole in the frame of the vehicle, or, if found desirable, the tubular element may be inserted through a hole provided therefor in a relatively thin support, in which event a nut may be connected to the element for clamping the switch to the support. Moreover, the element may be provided with flat portions, such as 37, so that the element may be disposed into an oblong hole in a support to prevent rotation of the switch about its longitudinal axis. Thus, it will be clearly evident that the opposite extremities of the operating member 5 project through and outwardly with respect to the end walls 8 and 9 of the switch casing, and that the extremity 35 is adapted for reciprocation within the tubular

bearing 30. It will also be noted that the operating member 5 is provided with a reduced portion or neck 38 intermediate its extremities.

The carrier 4 of insulating material which supports the bridge means 3 will now be described. The carrier 4 is preferably made from sheet stock, for example, paper or fibre Bakelite, and is constructed to include a lower enlarged generally rectangular portion 39, and an upper generally rectangular portion 40 of a size somewhat smaller than the enlarged portion, as clearly illustrated in Figure 3. Although it is not essential, the lower marginal edge of the enlarged portion 39 of the carrier is preferably provided with a recess 41 to form a pair of legs 42 which are adapted to slidably engage the bottom wall 6 of the switch casing when the switch is operated. A vertical entrance slot 43 extends inwardly from the recess 41 and terminates in a rounded seat 44. The slot 43 is of a width to permit entry of the reduced portion 38 of the operating member to the seat 44 when the carrier is dropped into place. It should be noted that the thickness of the carrier 4 is slightly less than the length of the reduced portion 38 so that the flat planar surfaces of the carrier more or less engage the abutments provided adjacent the extremities of the reduced portion 38 whereby to normally maintain the carrier in a substantially vertical position, or transverse with respect to the longitudinal axis of the operating member. This arrangement of the bridge carrier is considered unique as it is held in a position whereby but one end or marginal edge thereof is adapted to slidably engage a portion of the switch casing. In other words, the legs 42 of the enlarged portion 39 of the carrier are the only portions thereof which engage the switch casing. This is desirable, as less friction is encountered.

The bridge means 3 which is yieldably supported on the carrier 4 will now be described. The bridge means 3 is preferably generally box shape in form, and among other things, includes a rectangular top portion 45, a pair of side walls 46, and a pair of end walls 47 which partially enclose and slidably engage the upper portion 40 of the carrier. The top portion 45 is preferably provided with a pair of upstanding rounded contact portions 48, and each of the side walls is provided with a generally semi-circular aperture 49, which provide clearance so that the bridge 3 will not engage the abutment 33 of the tubular element or the helical spring 50 carried by the operating member 5 to interfere with the movement of the bridge. The side and end walls of the bridge and the upper portion of the carrier are so constructed and arranged that the bridge will not tilt or wobble when moved with respect to the contact means mounted on the carrier or switch back 2.

Resilient means, preferably in the form of a leaf spring 51 is disposed intermediate the top wall 45 of the bridge means and the upper marginal edge 52 of the bridge carrier. This spring includes a more or less central flat portion 53 which bears against the top wall 45 of the bridge means, and a pair of yieldable leg portions 54 which bear against the edge 52 of the carrier.

The helical spring 50, above referred to, surrounds the operating member 5 in a manner whereby one extremity of the spring bears against the end wall 8 of the switch casing and its opposite extremity against the bridge carrier 4 and the carrier against the abutment 33 so as to hold the contact portions 48 of the bridge means in

engagement with the contact plate 10, whereby to normally maintain the switch in an open circuit position.

Referring again to the operating member 5, it is evident that the extremity thereof which is supported in the end wall 8 of the switch casing has a flexible element 55 in the form of a metal cable preferably connected thereto in some desirable manner such as by swaging. An element 56 is preferably permanently connected to the cable so that the cable may be attached to some mechanism (not shown) for actuating the operating member to control the switch.

Thus, when the operating member is pulled outwardly by some mechanism through the intercession of the cable 55, one of the contact portions 48 of the bridge means 3 will remain in electrical engagement with the contact plate 10 and the other contact portion 48 will engage the contact head 23 of the rivet 22 to close an electrical circuit. Although the switch is preferably operated as just stated, it is to be understood that if found desirable, it may be operated by a member slidably disposed in the open ended tubular element 30.

Having thus described my invention, it is obvious that various modifications may be made in the same without departing from the spirit of the invention; and, therefore, I do not wish to be understood as limiting myself to the exact form, construction, arrangement, and combination of parts herein shown and described.

I claim:

1. An electric switch including, an open sided casing having a bottom wall, side walls, and end walls, a contact plate electrically connected to said casing closing off said open side, means on said plate engaging said end walls to prevent spreading of same, an aperture provided in said plate, a carrier of insulating material superimposed upon said plate secured to said casing, a contact carried by said carrier projecting into the aperture of the plate whereby to insulate the contact from said plate, a rod extending through the end walls of the casing, a relatively thin piece of insulation carried by said rod, the lower edge of said piece engaging the bottom wall of the casing, and bridge means carried by the upper edge of the piece normally engaging said contact plate to maintain the switch in an open circuit position, and said bridge means when moved to a predetermined position being adapted to engage said contact plate and said contact means carried by said carrier to place said switch in a circuit closing position.

2. A switch casing, an opening in said casing, bridge means movably arranged in said casing, a contact plate electrically connected to said casing and closing off said opening, an aperture provided in said contact plate, and a carrier of insulating material overlying at least a portion of said contact plate and provided with an electrical contact projecting into said aperture and out of electrical engagement with said contact plate, said bridge means, said contact plate and said electrical contact being so constructed and arranged that said bridge means may be moved to a position to engage said electrical contact and said plate to close an electrical circuit between said switch casing and said electrical contact.

3. An electric switch including, an open sided switch casing provided with side walls, a carrier carrying contact means mounted on and closing off the open side of said casing, switching mechanism disposed in said casing provided with

bridge means adapted to cooperate with said contact means, and additional contact means insulated from said first mentioned contact means secured between said carrier and at least one of the walls of said casing, said additional contact means being adapted to be engaged by said bridge means and providing means for holding at least one of said walls in a predetermined position with respect to another wall.

4. A switch including, a housing having an open side, a contact plate extending across said open side and connected to certain walls of the casing whereby to prevent spreading of the walls, insulating means overlying the contact plate, an opening in said plate, contact means carried by said insulating means projecting into said opening and out of contact with said plate, bridge means in said housing having a pair of contact portions normally engaging said plate, means for supporting the switch carried by a wall of the housing, and means extending into said supporting means and connected to said bridge means whereby the bridge means may be moved so that one of said contact portions may be brought into engagement with the contact means while the other contact portion remains in engagement with said plate.

5. A switch including, a casing having an open side, a contact plate extending across said open side electrically connected to opposite walls of the housing and preventing spreading of said walls, an insulator disposed on said plate, contact means carried by said insulator and insulated from said plate, means carried by one of said walls for supporting the switch with respect to a mounting, bridge means arranged in said casing and engaging said contact plate, means extending into the supporting means and connected to the bridge means whereby the bridge means may be moved to engage the contact means while remaining in engagement with the contact plate.

6. A switch including, a casing having an open side, a contact plate extending across said open side electrically connected to opposite walls of the housing and preventing spreading of said walls, an insulator disposed on said plate carrying contact means insulated from said plate, bridge means in said casing, and means connected to the bridge means whereby the bridge means may be moved to engage the contact plate and the contact means.

7. An electric switch including, an open sided switch casing provided with side walls, a carrier carrying contact means mounted on and closing off the open side of said casing, switching mechanism disposed in said casing provided with bridge means adapted to cooperate with said contact means, additional contact means insulated from said first mentioned contact means secured between said carrier and said casing, said additional contact means for holding at least a pair of the opposite walls of the casing together in manner whereby to prevent outward movement of same, and one of the side walls of the casing being provided with means for supporting the switch with respect to a mounting.

8. An electric switch including, an open sided switch casing provided with side walls, a carrier carrying contact means mounted on and closing off the open side of said casing, switching mechanism disposed in said casing provided with bridge means adapted to cooperate with said contact means, additional contact means insulated from said first mentioned contact means secured be-

tween said carrier and said casing, said additional contact means being adapted to be engaged by said bridge means and providing means for holding at least a pair of the opposite walls of the casing together in manner whereby to prevent outward movement of same, and one of the opposite side walls being provided with means for supporting the switch with respect to a mounting.

9. An electric switch comprising a casing, a contact plate carried by said casing, a carrier of insulation overlying said contact plate, an opening provided in said plate, a contact carried by said carrier accessible through said opening, and bridge means engaging said contact plate and engageable with said contact.
